RECESS BATHTUB

William H. Armstrong, Bloomfield Hills, Mich., assignor to Borg-Warner Corporation, a corporation of Illinois

Filed Mar. 25, 1965, Ser. No. 84,441

Term of patent 14 years

(Cl. D4—4)

Fig. 1

Fig. 2

Fig. 4

FIG. 1 is a top plan view of a recess bathtub showing my new design;

FIG. 2 is a front elevation view of the recess bathtub;

FIG. 3 is a sectional view taken along line 3—3 of FIG. 4; and

FIG. 4 is a sectional view taken along line 4—4 of FIG. 1.

The walls fragmentarily shown in broken lines are included for illustrative purposes only.

I claim:

The ornamental design for a recess bathtub, substantially as shown and described.
